UNITED STATES PATENT OFFICE.

IRA E. McCABE, OF CHICAGO, ILLINOIS.

LIGHT-OPERATED APPARATUS.

Continuation of application Serial No. 133,868, filed September 7, 1926. This application filed September 13, 1926. Serial No. 135,064.

This invention relates to improvements in light-actuated apparatus for the operation of switches, valves and like devices.

It is an object of this invention to provide a simple, inexpensive and reliable device which, when subjected to the rays of visible light, will operate to throw a switch, rotate a valve or impart the initial movement required to operate devices such as electric signals, electric sign flashing devices, electric alarms, fire extinguishers, liquid and gaseous feed controls and like devices.

While no claim is made herein to the broad idea of applying the absorption of visible light to accomplish physical work, the means and manner of accomplishing such result as hereinafter described is considered a continuing invention and further improvements upon that described in my prior pending application, Serial No. 133,868 filed September 7, 1926.

The accompanying sheets of drawing illustrate the preferable embodiments of this invention, however, minor changes may be made to such embodiments without departing from the scope of the invention.

In the drawings:

Figure 1 is a view in front elevation looking into a switch box casing embodying this invention and illustrating the operating parts in central vertical section.

Figure 2 is a view in side elevation of Figure 1 with the walls of the casing in section.

Figure 3 is a view in front elevation looking into an electric switch casing illustrating another form of switch operating mechanism.

Figure 4 is a view in transverse section through the center of Figure 3 with parts broken away.

Figure 5 is a view similar to Figure 1 of a valve operating device.

Figure 6 is a view in transverse vertical section of Figure 5.

Figure 7 is a detail view in section taken on line 5—5 of Figure 6.

Figure 8 is a view similar to Figure 5 showing another type of valve.

Figure 9 is a detail view in section taken on line 9—9 of Figure 8.

As set forth above, this invention is a continuation of the invention disclosed in my prior pending application, Serial No. 133,868, filed September 7, 1926, describing

a method and means for transmitting the energy of visible light rays to perform physical work. This invention relates to the application of this principle to impart initial movement to devices for opening and closing electric circuits and other fluid lines.

Figure 1 illustrates an embodiment of this invention as applied to a mechanism for opening and closing an electrical circuit and comprises a casing 1 having binding posts 2 mounted on the rear wall 3 adapted to connect a mercury tube switch 4 in the circuit to be controlled. This switch is of the commercial form, comprising a sealed glass tube containing sufficient mercury to close the circuit between two electrodes entering one end thereof when the tube is tilted in that direction and to break the circuit when the tube is tilted in the opposite direction. The switch 4 is mounted on a tilting support 5 preferably comprising a plate 5 mounted for rotation upon a centrally arranged pivot point 6 fixed to the rear wall of the casing 3 and the amount of rotation thereabout is limited in each direction by the lower corner 80 of the plate 5 contacting with the bottom wall of the casing.

The tilting plate 5 is normally held at one end of its movement and caused to rotate about its pivot to the other end of its movement by mounting thereon two sealed gas containers 7 and 8, preferably of glass, joined at their bottoms by a restricted or tubular connection 9, preferably of the same material, connecting with the interiors thereof. The enlarged containers 7 and 8 are preferably similar in shape to the commercial electric light bulb and are secured adjacent each end of the plate by clips 10 mounted thereon while the interconnecting portion 9 and mercury tube switch 4 are preferably supported on plate 5 by clips 11 secured centrally thereon below its pivot point. A liquid seal 12 adapted to flow through the connecting portion 9 from one bulb to the other is placed therein before the bulbs are sealed. This seal may be of any suitable liquid having sufficient weight and volume to accomplish its purpose. As above stated, it is preferable to form the apparatus 7 and 8 and their connecting portion 9 of glass and in accordance with this invention one bulb is formed of a colored glass adapted to absorb more energy from the rays of visible light than the other bulb 110

8 and the liquid seal 12 is so arranged before the bulbs 7 and 8 are sealed that the majority of the liquid 12 is contained in and adjacent the bulb 7 whereby the plate 5 in the absence of visible light is normally tilted to the end of its movement in the direction of bulb 7. When rays of visible light enter directly into casing 1 and fall upon the bulbs 7 and 8 the colored bulb 7, on account of the medium of which it is constructed, absorbs more energy from the light rays impinging upon it than bulb 8 so that the temperature of its walls is increased over that of the other bulb 8, expands the air or gas therein above the seal 12 creating a greater internal pressure than that in bulb 8, whereby the level of the seal 12 is forced downward in bulb 7 causing the liquid to flow through the connecting portion 9 and enter into the bottom of bulb 8 and as the majority of the fluid is forced over into bulb 8, the plate will be caused to rotate about its pivot until the corner below bulb 8 encounters the bottom wall of the casing. Likewise, upon the removal of the source of light, the increased temperature of the walls of bulb 7 will be radiated into the surrounding atmosphere, decreasing the internal pressure therein, whereupon the liquid will be returned to its original normal position by the pressure in bulb 8 and the plate caused by the weight of liquid 12 to rotate about the pivot to its original or normal position.

The terminals of mercury switch 4 are preferably connected by flexible leads 14 to the binding posts 2 and the tube is inserted in its supporting clips 11 with its terminals adjacent bulb 8, if the circuit is to be closed by exposing the switch to visible light, and with its terminals adjacent bulb 7 is the circuit to be normally closed and opened when the switch is exposed to visible light.

In the remaining figures of the drawing similar reference numerals are applied to indicate similar parts.

Figures 3 and 4 illustrate an apparatus similar in general construction to that above described in which the pivot point 6 of the supporting plate 5 is a shaft mounted in a U-shaped bracket 6^a secured to the bottom wall of casing 1 and the plate is adapted to be adjustably mounted upon this shaft by providing a central vertical slot 14 in supporting plate to receive the shaft and be received thereto by nuts on each side of the shaft and the amount of its movement about this pivot adjusted by the set screws 15 arranged in the bottom walls of the casing adapted to be engaged by the bottom corners of the plate at each end of its movement. In this form, the terminals of the mercury tube switch 4 are adjacent the colored bulb 7 so that the circuit is normally closed and

will be opened when the switch is exposed to visible light.

In the construction illustrated in Figures 3 and 4, plate 5 may be so adjusted as to alter the time of operation after exposure 70 to visible light, as well as the time of returning to normal upon the removal of the source of light, and also the rapidity of rotation of the supporting plate 5 after the initial movement has been imparted to it, 75 as well as the momentum of such movement, to meet the varying conditions and requirements of the various uses to which this device is adapted, by the proper adjustment of the set screws 15 in the bottom casing and 80 the independent adjustment of the plate 5 upon its pivot shaft 6.

Figures 5, 6, and 7 illustrate an embodiment of this invention as applied to operate a fluid line valve. In this case the pivot 6^a of the carrying plate 5 is rotatably mounted in bearings in a U-shaped bracket 6^a secured to the bottom and rear walls of casing 1 and is in the form of a shaft having its rear end enlarged forming a shoulder 16 adjacent which the carrying plate is secured by nut 17 engaging a screw threaded portion of the shaft so that the shaft rotates with the tilting of plate 5. This enlarged portion of the shaft extends through the rear wall 3 of the casing and is formed integral with, or secured to, a rotatable valve head 18 mounted in concentric seat within a valve casing 19 preferably provided on its forward end with a reduced shoulder portion 20 also passing through the rear wall 3 of the casing and rear arm of the U-shaped bracket 6^a and secured in place, and securing the bracket arm to the rear casing wall, by a nut 21, said valve casing forming a bearing 105 for the rear end of the shaft 6. The valve head 18 is provided with a port 22 passing diametrically therethrough and adapted to register with ports opening into housings 23 in the valve casing which receive the tubes 24 of the fluid to be controlled. Since the nut 17 allows an adjustment of the plate 5 upon shaft 6, the desired relation between port 22, the tubes 24 and plate 5 is readily established.

Figures 8 and 9 illustrate a form of this device similar to that shown and described in Figures 5, 6, and 7 differing only in the type of valve enclosed in casing 19. In this case the cylindrical chamber 25 within the casing 19 is closed at its exterior end by a screw plug 26 and at its opposite end by a circular plate 27 formed integral with or secured to the shoulder portion 16 of the shaft 6 and adapted to rotate in a seat 115 formed in the valve casing. The tubes 24 of the fluid line enter the chamber 25 at right angles to each other with the vertical one preferably entering the bottom of the casing 19 and at one side of the vertical cen- 120 125 130

ter line of the chamber which is preferably provided with a corresponding opening at the upper side therein. A reciprocating valve stem 28 having a head 29 adapted to be seated upon the port opening into the housing of the vertical tube 24 is guided by a screw threaded sleeve 30 threaded into the upper opening and is provided with an outstanding collar 31 intermediate its length which is adapted to be engaged by a stud 32 carried on plate 27 near its circumference, so that when the plate is rotated to cause the stud to engage the underside of the collar 31, the valve head is lifted from its seat and when the plate is rotated in the opposite direction the valve will be seated by its own weight aided by the pressure of the fluid line also the horizontal tube 24. If the flow of the fluid line is in the opposite direction, the shaft 26 is so adjusted that stud 32 will normally engage the upper side of the collar 30 and upon rotation in that direction will seat the valve and upon rotation in the opposite direction will pass out of contact and allow the flow of the fluid line to list the stem 38 and unseat the valve. Since the stud 32 is rotatable with shaft 6 which is adjustably secured to the carrying plate 5, the desired relation between plate 5, shaft 6 and stud 32 may be readily established. While this device is illustrated and described with the containers separated equidistantly from a pivot point, it is to be

understood that the movement of the liquid from adjacent each container to adjacent the other imparts a movement to the device which movement is employed to accomplish the desired work irrespective of the manner in which the containers are separated.

What I claim is:

A light operated control means, comprising two spaced apart interconnected glass containers having a liquid seal with a balance of pressure on each side thereof with said seal normally adjacent one container, the walls of which are of a colored glass adapted upon exposure to visible light to transmute more energy from the absorbed rays of the visible spectrum than the other container, which absorbed energy acts to increase the internal pressure within that container and move the liquid seal in the direction of the other container, a pivoted carrying plate mounting such containers equidistantly from the pivot point, and a valve in a liquid fuel line adapted to be controlled by a rotatable head operatively connected to the carrying plate and having a stud mounted thereon adjacent its edge coacting with a collar upon a reciprocating valve stem to open the line as the plate is tilted from one side to the other about its pivotal point upon movement of the liquid seal and allow the closing of the line as the plate is tilted in the opposite direction.

IRA E. McCABE.
